UNITED STATES PATENT OFFICE

PAUL C. CHAPMAN, OF CHICAGO, ILLINOIS, ASSIGNOR TO PULLMAN CAR AND MANUFACTURING CORPORATION, OF CHICAGO, ILLINOIS, A CORPORATION OF ILLINOIS

DESIGN FOR A BRACKET LAMP

Application filed June 12, 1929. Serial No. 31,636. Term of patent 14 years.

To all whom it may concern:

Be it known that I, PAUL C. CHAPMAN, a citizen of the United States, and resident of Chicago, county of Cook, and State of Illinois, have invented a new, original, and ornamental Design for Bracket Lamps, of which the following is a specification, reference being had to the accompanying drawings, forming a part thereof.

Fig. 1 is a plan view of the bracket lamp in accordance with the present design.

Fig. 2 is a front elevational view of the bracket lamp, and

Fig. 3 is a side elevational view of the bracket lamp showing the design of the lamp in Figure 2.

I claim:

The ornamental design for a bracket lamp substantially as shown.

In witness whereof I have hereto set my hand this 8th day of June, 1929.

PAUL CROSS CHAPMAN.
